UNITED STATES PATENT OFFICE.

ALBERT FISCHER, OF BERGEDORF-HAMBURG, GERMANY, ASSIGNOR TO THE FIRM
BERGEDORFER EISENWERK AKTIENGESELLSCHAFT, OF BERGEDORF-HAMBURG,
GERMANY.

STERILIZING DEVICE.

Application filed May 15, 1925, Serial No. 30,495, and in Germany July 2, 1924.

My invention relates to devices for sterilizing liquids and more especially to devices in which liquids, for instance milk, are subjected to protracted heating. In the protracted heating of liquids for sterilizing purposes the temperature is kept comparatively low, but is allowed to act on the liquid a comparatively long time. Sterilization should lead to a destruction of all germs without however depriving the liquid of its desirable qualities.

In devices of this kind as heretofore constructed the delivery and discharge of the liquid was as a rule effected by means of cocks or valves. Such parts, however, involve drawbacks which may render the treatment of the liquid a total failure, as part of the liquid which may not have been subjected to the action of heat for a sufficient length of time, may be mixed with the sterilized liquid which is thus polluted.

It is an object of my invention to overcome these drawbacks by eliminating valves or cocks altogether. To this end I provide a plurality of chambers or tanks which are combined into a unit adapted to rotate about a horizontal or substantially horizontal axis, such chambers or tanks being automatically and successively filled and discharged during each revolution.

In the drawings affixed to this specification and forming part thereof several devices embodying my invention are illustrated diagrammatically by way of example.

In the drawings—

Fig. 1 is a longitudinal section of one modification,

Fig. 2 is a similar view illustrating a second modification.

Figs. 3 and 4 are sections on the lines 3—3 and 4—4 in Fig. 1, respectively.

Referring to the drawings, 1 is a drum provided with end plates 2 and 3 and surrounded by a heating jacket 4. 5 and 6 are tubular trunnions at the end plates 2 and 3 supported on pairs of rollers 7, 7, and 8, 8, respectively. The drum 1 can thus rotate about a horizontal or substantially horizontal axis and any suitable means, not shown, may be employed for slowly rotating it.

9, 10, 11 and 12 are longitudinal partitions which subdivide the drum into four compartments *a*, *b*, *c*, and *d*. It will be understood that any number of partitions and compartments may be provided and that, instead of forming compartments by partitions as shown, it is also possible to arrange separate tanks in a rotary frame.

13 is a pipe for delivering the liquid to be treated to a chamber 14 in the trunnion 6, this pipe being arranged in the axis of the drum so as not to interfere with its rotation. The inner end of the pipe 13 is bent radially at 16, and 17 is a float valve adapted to slide on said bend and to close it when the liquid has attained the level *L*, as shown in Fig. 1. Means such as a stuffing box (not shown) may be provided in the cover 15 at the front end of the chamber 14 through which the pipe 13 passes, but all packing means may be dispensed with as the level of the liquid is below the pipe 13 and the liquid has no tendency to splash on account of the slow rotation of the drum. Delivery pipes 18, 19, 20 and 21 connect each of the chambers *a*, *b*, *c* and *d* with the chamber 14 in the trunnion 6, such pipes opening into the chambers near the periphery of the drum. It will be understood that by these means the liquid is maintained at the same level in the chamber 14 and those chambers *a*, *b*, *c*, *d*, which are in a corresponding position.

Each chamber is connected with a discharge pipe 22, 23, 24, 25. 26 is a discharge tube connected with the several discharge pipes.

Vent pipes 28 may be provided near the inner ends of the chambers in order to remove the air during the filling periods.

Suitable means (not shown) may be provided for supplying a heating medium or liquid to the jacket 4. The jacket may however also be dispensed with altogether and hot liquid may be supplied to the device from a separate heater. Such jackets may also be provided at the end plates, as shown in Fig. 2, where a chamber is formed at the end plate 2 by a plate 27. It is also possible to construct the partitions 9, 10, 11 and 12

- as hollow walls and to cause heating liquid or fluid to circulate therein, as indicated at 9' in Fig. 3. It will be understood that in an apparatus provided with heating jackets 5 as described it is possible to supply hot liquid to the device and to maintain it at a suitable temperature, or cold liquid may be supplied to the device and gradually heated therein.
- 10 When the drum 1 is rotating slowly, as indicated by the arrow in Fig. 4, the liquid which is supplied to the chamber 14 through the pipe 13, is conducted to those chambers, which are in the lowest positions at the time, 15 through the pipes 18, 19, 20 and 21, respectively. In the position shown in Fig. 4 the chamber *d* is being filled through the pipe 18. As soon as the opening of the pipe 19 in the chamber *c* gets below the liquid level 20 *L-L*, the filling period of the chamber *c* begins. No liquid is delivered to the pipes 20 and 21 of the chambers *b* and *a* as their openings in the chamber 14 are above the liquid level. The filling period of a chamber 25 is finished when the partition adjoining a pipe is substantially horizontal (*g* in Fig. 4). In this position the delivery and discharge pipes of a chamber are above the liquid level. It will be understood that the 30 liquid is continuously agitated by the rotation of the drum also in those chambers which are not being filled or discharged. The discharge period of a filled chamber begins when the opening of the corresponding 35 discharge pipe gets below the liquid level in that chamber. The openings of the delivery pipes are always above the liquid level in any position so that the liquid can never return to the chamber 14. When a discharge 40 pipe has moved past its horizontal position, intermediate conditions will prevail in the corresponding chamber, so that this chamber is neither filled nor discharged. As soon, however, as the opening of a delivery 45 pipe gets below the level of liquid in the chamber 14, the filling period of that chamber will begin. It is important that the openings of the discharge pipes be near the periphery of the drum, though not so near as 50 the openings of the delivery pipes 20. Any scum or other floating matter which may collect on the surface of the liquid is discharged first. As soon as the discharging period has begun, a siphon action is exerted on the liquid 55 and the greater part of the scum is removed immediately. This is very important from the point of view of thorough sterilization.
- I wish it to be understood that I do not 60 desire to be limited to the exact details of construction shown and described, for obvious modifications will occur to a person skilled in the art.
- I claim:
- 65 1. A device for sterilizing liquids com-

prising a plurality of containers arranged for simultaneous rotation about a common axis, an axially arranged rotary liquid supply, liquid governed means in said liquid supply for regulating the inflow of fresh 70 liquid, communication between said liquid supply and a point near the outer periphery of each container and an exhaust extending from a point near the outer periphery of each container to an axial exhaust port. 75

2. A device for sterilizing liquids comprising a rotary drum, substantially radial partitions defining chambers in said drum, an axially arranged liquid supply chamber adapted to rotate with said drum, means for 80 keeping constant the liquid level in said supply, a radial filling tube establishing communication between said supply and each chamber and ending at a point near the outer periphery of said tube and a radial exhaust tube extending radially from a common axial exhaust port into each chamber and ending at a point near the outer periphery of said drum. 85

3. A device for sterilizing liquids comprising a rotary drum, a heating jacket surrounding said drum, substantially radial partitions defining chambers in said drum, an axially arranged liquid supply chamber adapted to rotate with said drum, means for 90 keeping constant the liquid level in said supply, a radial filling tube establishing communication between said supply and each chamber and ending at a point near the outer periphery of said tube and a radial exhaust 95 tube extending radially from a common axial exhaust port into each chamber and ending at a point near the outer periphery of said drum. 100

4. A device for sterilizing liquids comprising a rotary drum, substantially radial partitions defining chambers in said drum, an axially arranged liquid supply chamber adapted to rotate with said drum, means for 105 keeping constant the liquid level in said supply, a radial filling tube establishing communication between said supply and each chamber and ending at a point near the outer periphery of said tube, a radial exhaust tube extending radially from a common axial exhaust port into each chamber and ending at a point near the outer periphery of said drum, and a vent pipe for each 110 chamber. 115

5. A device for sterilizing liquids comprising a rotary drum, partitions defining compartments in said drum, automatic means operated by the rotation of said drum for supplying liquid to and discharging liquid from said compartments, and means 120 for maintaining the liquid supplied at a constant level below the axis of said rotary drum. 125

6. A device for sterilizing liquids comprising a rotary drum, partitions defining 130

compartments in said drum, a co-axial hollow cylinder arranged at one end of said drum, means for supplying liquid to said cylinder, pipes connecting said cylinder with 5 said compartments, and opening at a given distance from the periphery of said drum, and a discharge pipe in each compartment

opening at a distance from the periphery of said drum which is greater than the distance of the openings of said supply pipes from 10 said periphery.

In testimony whereof I affix my signature.

ALBERT FISCHER.
